UNITED STATES PATENT OFFICE

PAUL B. RENFREW, OF FORT WAYNE, INDIANA, ASSIGNOR TO S. F. BOWSER & COMPANY, INC., OF FORT WAYNE, INDIANA, A CORPORATION OF INDIANA

DESIGN FOR A CASING FOR A DISPENSING APPARATUS

Application filed April 10, 1930. Serial No. 35,209. Term of patent 14 years.

To all whom it may concern:

Be it known that I, PAUL B. RENFREW, a citizen of the United States, residing at Fort Wayne, in the county of Allen and State of Indiana, have invented a new, original, and ornamental Design for Casing for a Dispensing Apparatus, of which the following is a specification, reference being made to the accompanying drawing, forming a part thereof.

The accompanying drawing shows a perspective view of the casing for a dispensing apparatus embodying my new design.

The casing for a dispensing apparatus embodying my new design when viewed from the opposite side will appear substantially the same as shown in the accompanying drawing.

I claim:

The ornamental design for a casing for a dispensing apparatus, as shown and described.

Fort Wayne, Indiana, April 7th, 1930.

PAUL B. RENFREW.
